US00D529507S

(12) United States Design Patent (10) Patent No.: US D529,507 S
Cummins (45) Date of Patent:  Oct. 3, 2006

(54) IMAGE FOR A PORTION OF A DISPLAY SCREEN

(75) Inventor: Charles Cummins, Seattle, WA (US)

(73) Assignee: Microsoft Corporation, Redmond, WA (US)

() Term: 14 Years

(21) Appl. No.: 29/228,350

(22) Filed: Apr. 22, 2005

(51) LOC (8) Cl. 14-04

(52) U.S. Cl. D14/485

(58) Field of Classification Search 715/500.1, 715/501.1, 526, 530-31, 539, 708, 711, 717, 715/723, 726, 733, 738, 753, 762, 763-4, 715/767-69, 778-82, 788, 790, 793-94, 715/797-8, 802-10, 835-40, 848-856, 862-63, 715/976, 978; D14/485-94; D18/24-33; D20/40, 11; D19/6; D21/324-33; 434/43, 434/38; 382/305; 400/76; 710/5, 73; 707/102, 707/2; 463/32, 16; 717/170; 705/26, 27; 345/757, 345/782, 848, 852, 850, 809, 837, 798, 752, 345/163, 156, 537, 474, 836, 419, 649, 656, 345/659, 426, 427, 582, 428, 440, 660, 634, 345/902, 418, 629

(57) CLAIM

I claim the ornamental design for an image for a portion of a display screen, as shown and described.

DESCRIPTION

The FIGURE is a front view of an image for a portion of a display screen showing my new design.

The broken line showing of the remainder of the display screen is for illustrative purposes only and forms no part of the claimed design.

1 Claim, 1 Drawing Sheet
